RIMMON C. FAY, OF PAWTUCKET, RHODE ISLAND, AND FREDERICK L. FAY, OF EAST BROOKFIELD, MASSACHUSETTS, ASSIGNEES TO THE EASTON & BURNHAM MACHINE COMPANY, OF PAWTUCKET, RHODE ISLAND.

WINDING-MACHINE.

SPECIFICATION forming part of Letters Patent No. 707,684, dated August 26, 1902.

Application filed October 10, 1901. Serial No. 78,215. (No model.)

To all whom it may concern:

Be it known that we, RIMMON C. FAY, residing at Pawtucket, Providence county, State of Rhode Island, and FREDERICK L. FAY, residing at East Brookfield, Worcester county, State of Massachusetts, citizens of the United States of America, have invented certain new and useful Improvements in Winding-Machines, of which the following is a specification.

Our invention relates to certain novel improvements in "winding-machines," so called—that is, machines adapted to automatically wind a continuous length of yarn or thread from a suitable source of supply, as a bobbin, spool, or cop, onto a revolving quill, tube, or cop-holder, the result being to produce a cop or "package" having the lay or wind of the yarn substantially uniform throughout the cop, the yarn load thus wound being compact and not liable to become broken or disarranged and having the coils or convolutions of the several layers crossing one another, so as to produce a close wind.

We are aware that machines of the class or type forming the subject of this application and capable of producing cops having a close wind have been devised prior to our invention. A machine of this character is shown and described in United States Patent No. 525,085, dated August 28, 1894.

The object we seek to attain is to produce a winding-machine having a greater degree of efficiency than is possessed by analogous machines heretofore devised—that is to say, in our improved winding-machine the cop-holding spindle is vertically arranged and more conveniently accessible to the attendant, the spindle-driving mechanism is less complicated, it is capable of being readily adjusted as desired, so as to produce cylindrical or cone shaped cops or packages. Moreover, the machine as a whole is simple in construction, strong yet light, and comparatively inexpensive.

In carrying out our invention the machine consists, essentially, of a revolving cam and a vertically-reciprocating yarn-guide actuated thereby, a vertically-arranged revolving cop-carrying spindle located contiguous

to and adapted to receive the yarn from said guide, a laterally-movable frame having said spindle mounted therein, variable driving mechanism for actuating said cam and spindle having its movements automatically controlled by the cop itself as the latter is built up and increased in diameter, whereby the relative velocity ratios of the cam and spindle are maintained, while at the same time the speed is gradually diminished, and a yarn tension device automatically regulated by the said cop, thus reducing the tension upon the yarn while the cop increases in size, all as will be more fully hereinafter set forth and claimed.

In the accompanying three sheets of drawings, illustrating our improvements in winding-machines, Figure 1 is a front side elevation, in partial section, showing a portion of the machine as in operation. Fig. 2 is a corresponding transverse sectional view taken on line 2 2 of Fig. 1. Fig. 3 is a horizontal sectional view taken on line 3 3 of Fig. 1. Fig. 4 is a plan or partial horizontal sectional view taken on line 4 4 of Fig. 3, showing the driving mechanism. Fig. 5 is a rear side elevation of the spindle-carrying frame, showing the cam through which the speed of the driving-belt is automatically changed. Fig. 6 is a sectional view of the tension device. Fig. 7 is a corresponding side elevation. Fig. 8 is a plan view showing a modification of the belt-shipping device, and Fig. 9 is a sectional view taken substantially on line 9 9 of Fig. 8.

The following is a more detailed description of our improved winding-machine:

We would state in passing that W indicates the winding device proper, the same being mounted in or on suitable standards or legs, as A, the longitudinally-extending top bed or table a, secured thereto, the front upper frame or tie b, and the lower tie m. The length of said table, &c., may be made so as to carry a series of the said winding devices W, each capable of being independently actuated and controlled as desired. In Fig. 1 is represented a portion of such organized machine, the winding or cop-carrying spindles H being, say, about twelve inches apart.

As drawn, a suitably-located continuously-

revolving driving-shaft s is mounted in the lower portion of the machine, from which shaft is transmitted the power for actuating the several winding mechanisms. To this 5 shaft is secured a yielding driver-pulley F' , (one for each winding head or device W ,) consisting of the fixed disk f and the slideable fellow disk member f' , connected thereto by the two transverse pins or studs f^2 , on which 10 latter are mounted outer helical springs f^3 , adapted to keep the faces of the revolving disks in frictional engagement with and 15 actuate the intermediate power-transmitting and shipper wheel E . The outer portion of the adjacent faces of said disks is beveled divergently, as at f^4 , the corresponding portion of the wheel E also being beveled, as clearly shown.

In Fig. 2 is represented a table a' , having 20 depending brackets a^2 secured thereto, in which is mounted a short revoluble shaft a^3 , on which latter is secured a yielding driven pulley F , constructed and arranged for operation substantially the same as the pulley 25 F' just described. The shaft a^3 is located directly above shaft s and so arranged that its speed will vary with respect to that of the driving-pulley F' , according to the position of the interposed shipper-wheel E —that is to 30 say, the latter (mounted to revolve freely on a shaft b^6 , secured in a yoke b^5 of the shipper-lever b^2 , in turn pivoted at b^4 to a stationary bracket b') is capable of being vibrated in a 35 vertical direction, whereby the shipper-wheel E upon being elevated is withdrawn a corresponding extent from the lower or driving pulley, thus increasing the speed of pulley F , a reversal of the operation producing a 40 reduction of the speed ratio, the function of the springs f^3 being to insure frictional engagement of the working surfaces of the several pulleys.

The cop-spindle H , &c., soon to be described, as well as the cam C , revolve at different 45 predetermined rates of speed, the former being much the faster. We prefer to make the relative diameters of the said pulleys F F' and shipper-wheel E such that when the wheel E is in the lowest position, substantially as 50 shown in Fig. 2, the cop-spindle will be driven at its minimum speed. Said pulley when elevated into a corresponding engagement with the pulley F will rotate the spindle at substantially the maximum speed, or, say, sev- 55 enty-five per cent. in excess of the minimum. The relative velocities of the cam and cop-spindles to each other, however, remain the same, as before stated. Upon elevating the wheel E until it is wholly disengaged from the 60 revolving driving-pulley F' the winding-head W will be instantly brought to a state of rest. This is readily effected by simply depressing the handle b^3 of the shipper-lever. The said front frame b is provided with upper and lower 65 ways, in which the carrier-plate B is mounted edgewise and adapted to slide longitudinally therein, the extent of said movement being

at least equal to the maximum thickness of the yarn load capable of being wound upon the cop. At the proper point the frame b is 70 provided with suitable bearings for the vertical revolving shaft c^2 . The latter extends above the table or bed a and has secured thereon the barrel-cam C , the same having a continuous cam-groove c formed in its peripheral 75 surface capable of imparting the proper reciprocating movement or transverse action to the light vertically-guided yarn-guide d . This latter has a cross-head d' , adapted to slide freely in vertical ways d^3 , secured to the exterior of the stationary cam-casing c^3 , removably fastened to the bed a . The casing has a vertical slot through which the yarn-guide extends. It also supports a freely-turning vertical roll d^2 , located contiguous to the 80 yarn-guide. (See Figs. 1 and 3.) To the front side of said carrier-plate B is secured a frame or housing H' , in which are mounted upper and lower bearings h^1 h^4 , respectively. (See Figs. 1 and 2.) These bearings form 85 suitable supports for the revolving cop-spindle H . In case it is desired to produce a cylindrical-shaped cop or package the axis of the spindle will stand parallel with that of the said guide-roll d^2 , as shown in the drawings. In order to produce cone-shaped cops, the spindle is provided with a correspondingly-shaped tube or quill, followed by loosening the securing-screws h^2 of the housing H' and swinging the latter until the side of 90 the tube is parallel with that of the guide-roll, the slotted openings h^3 at the same time readily permitting the adjustment to be made, after which the screws are retightened. 95

Owing to difference in size, quality, and 100 kind of yarn or thread to be wound into cops, we deem it desirable to provide the machine with means whereby the normal rate of speed of the cop-spindle may be slightly increased or diminished in a very close and accurate 105 manner, and this, too, independently of the change in speed, due to and effected automatically by the cop itself as it increases in diameter. Mechanism for thus adjusting or 110 regulating the speed of the cop-spindle is as 115 follows: The cop-spindle H has a belt-driven pulley I secured thereon, as shown in Figs. 1 and 2, and inclosed in the casing H' . The 120 said pulley consists of the combined hub and head or top portion i' , the vertically-slidable tapering rim member i , having its upper edge adapted to enter an annular or guide groove i^2 , formed in the outer part of the said head i' , and suitably-mounted interior springs i^5 , interposed between the parts i i' for keeping 125 the latter normally separated. The lower end of the pulley-hub is screw-threaded and provided with an annular nut i^3 . By turning the nut in the proper direction the pulley-rim will be forced upwardly into said 130 groove i^2 , (resisted by the springs i^5 ,) thereby slightly reducing the working diameter of the pulley—that is to say, the outer face of the pulley-rim is beveled, its greatest diameter

being at the top edge, the range of movement afforded by the depth of the said groove being such that as the rim is elevated the traveling flat belt α will impart a slightly-accelerated speed or lead to the spindle, the degree of adjustment being accurately secured by the nut i^3 , the latter being accessible through an opening i^4 , formed in the casing H' . Since the tendency of a traveling belt

5 is to "run" to the high side of the pulley, we provide the latter with an upper guard-flange, as clearly shown, thereby preventing the belt from leaving the pulley. To the front lower side of the said frame b and below the pulley I is secured a bracket k^3 , carrying a combined idler and take-up pulley k , the same being mounted to turn freely on a stud screwed into a nut k' , fitted to slide laterally in said bracket, the adjustment being effected after 10 first partially unscrewing the stud, followed by resecuring it in position. We prefer to make the face of the pulley somewhat "crowning" and inclose the same in a suitable casing or guard k^2 , all as clearly shown.

15 25 The cam-carrying shaft c^2 is actuated as follows: To the back of said frame b is secured a bracket g' , having a horizontal shaft g mounted to turn therein. To one end of this shaft is secured a wide pulley g^2 , while 20 its opposite end carries, as drawn, a spiral toothed gear g^3 , working into and driving a similar but larger gear g^4 , the latter in turn being secured to the vertical shaft c^2 , fitted to revolve in the frame b and carrying the 25 cam C for actuating the yarn-guide d' . (See Figs. 2 and 4.)

30 The manner of driving the cam-shaft c^2 and the cop-spindle H is substantially as follows: The endless open belt α (see Figs. 2 and 4) passes from the wide driven pulley F , revolving in a vertical plane, to and around the idler-pulley k , adapted to revolve in a horizontal plane, thence around the wide pulley g^2 , secured to the horizontal gear-carrying 35 shaft g , and from the latter pulley to and around the adjustable pulley I , (also adapted to revolve in a horizontal plane,) secured to said cop-spindle, and thence back to the pulley F , thus completing the circuit. The pulley k is adapted to be adjusted in a lateral direction, so as to maintain a substantially uniform tension upon the belt, thereby revolving the pulleys without slip. It will be seen, referring to Fig. 4, that the two pulleys 40 45 F and g^2 are of sufficient width or face to allow a considerable lateral travel thereon of the moving narrow belt α , said travel corresponding to the maximum endwise movement of the plate B , in which the revolving pulleys I and k are mounted. This movement of the plate, &c., is equal to the maximum thickness of the yarn load upon the cop, as hereinbefore stated. It will be seen, too, that as thus constructed the length of the belt remains the same with respect to the pulleys at 50 all times and irrespective of the size of the cop being produced. As thus arranged the

55 pulleys F and g^2 will revolve in opposite directions and the two spindles c^2 and H also in opposite directions, but at different rates of speed.

60 From the foregoing it is clear that as the cop P increases in diameter, as in building up, it will be gradually forced laterally toward the right, thereby carrying with it the easily-slid- 75 able plate B and the parts attached thereto. The drawings represent the position and relation of the several mechanisms when the cop is practically completed. In building the cop its traveling outer surface is in substantially continuous frictional engagement with the freely-turning guide-roll d' , the degree of pressure being controlled by the attendant as desired—that is to say, the attendant simply forces the 80 slideable plate B , carrying the cop-spindle, &c., endwise in the desired direction, thereby keeping the cop's surface in yielding engagement with the guide-roll, the pressure between the two surfaces being due to the force exerted by the attendant. A short rod or 85 handle (not shown) may be inserted in the small opening i^4 , formed in the casing H , thus affording a convenient means for effecting the movements of the parts manually. If desired, a normal degree of pressure may be produced by means of a spring or weight attached 90 to the plate in any well-known or obvious manner.

95 The yarn-tension device N , Figs. 6 and 7, possesses some well-known features. For example, the fixed stud has its outer end n^4 screw-threaded and provided with a nut n^6 , adapted to regulate the force of a light helical spring n^5 , interposed between the nut and the pair of friction-disks n' , thereby producing a normal tension upon the yarn or thread in its passage between the disks. Our improvement resides in providing the head of the standard or bracket n with a fixed cam-collar n^2 and a loose swinging fellow cam member n^3 , interposed between the collar n^2 and the adjacent disk n' . The collar n^2 has a downwardly-extending arm n^7 , jointed at its lower end to a rod or link n^8 , Figs. 1 and 2, attached to and moving in unison with the 100 sliding spindle-carrying plate B . The tension device N is fixed to the bed a of the machine at a suitable point, so that the yarn t will lead direct therefrom to the eye of the vertically-reciprocating yarn-guide d . (See also 105 Fig. 3.) As thus arranged it will be seen that the length of yarn between the tension-disks and said guide remains practically the same at all positions of the guide. Therefore the normal tension upon the yarn is substantially uniform with respect to the guide's 110 movements. In view of the fact that the tension upon the yarn should decrease with the increasing diameter of the cop, the gradual movement of the plate B will by means 115 of the said connection n^8 swing the arm n^7 a corresponding extent, thus slightly decreasing the space between the cam-collars and correspondingly automatically reducing the 120 125 130

pressure upon the yarn between the friction-disks n' .

In order to provide means for automatically changing the speed of the cop-spindle and cam, so as to maintain as far as practicable a uniform peripheral or surface velocity to the cop throughout the building operation, we have devised the following mechanism: At a suitable point the frame b is drilled to receive and form a bearing for the vertically-movable rod e , jointed to the said shipper-lever b^2 , the connection being forward of the lever-fulcrum b^3 , as clearly shown in Fig. 2. To the back of the plate B is secured a suitable cam e^2 , (see also Fig. 5,) adapted to be in continuous frictional engagement with a stud or roll e' , mounted on a collar adjustably secured to the said rod e . A spring e^3 is interposed between the collar and the lower portion of the frame, as shown in Fig. 2. As thus drawn the force of the spring operates to depress the shipper-wheel E and also to maintain the roll e' in frictional contact with the cam e^2 . It is to be understood that the construction and relation of the several parts to one another are such that the joint action of the spring and moving cam operates automatically to gradually reduce the speed of the cop and cam spindles (as the cop increases in diameter) by gradually withdrawing the shipper-wheel E from the pulley F and forcing it downwardly a corresponding extent into the beveled portion of the driving-pulley F' , the position of the wheel, &c., corresponding with the minimum working speed and maximum diameter of the cop being substantially as represented in the drawings.

The manner of operating our improved winding-machine is substantially as follows, assuming first, however, that a cop tube or quill has been placed upon the spindle H and that a suitable supply-cop j , from which the yarn is to be unwound, is mounted on the stationary spindle m^2 , secured to a bracket m' , in turn secured to the spindle-rail m , and having the yarn or thread t passing upwardly from the cop j , through the eye t' , then between the tension-disks n' to the yarn guide or traveler d , and finally onto the cop-tube. The plate B is now moved toward the left until the cop-tube engages the roll d^2 , thereby at the same time swinging the tension-arm n^2 to the left and automatically increasing the friction between the disks n' . This movement of the plate also carries the driving-belt x in a lateral direction a corresponding distance upon the pulleys F and g^2 , the attendant meanwhile keeping the shipper-lever sufficiently depressed (thereby contracting the spring e^3 of the rod e) to disengage the shipper-wheel E from the continuously-revolving driving-pulley F' . Now upon releasing the shipper-lever the force of the said spring elevates the shipper and its rod a short distance or until the roll e' is arrested by the heel or lower part of the cam e^2 , the result being to depress the shipper-wheel E , so that its outer

portion will just enter between and frictionally engage the yielding members of the continuously-revolving driving-pulley F' and be actuated thereby, the speed of the cop-spindle then being at its maximum. As drawn the relative velocities of the cop and cam spindles are such that the former makes eight revolutions to one of the cam, so that as the cop revolves there will be eight coils or convolutions of the yarn wound upon it during each revolution of the cam or double reciprocation of the yarn-guide d . As the cop increases in diameter by the additional layers of coils the plate B , &c., will be automatically advanced thereby a corresponding extent, and since the spring e^3 serves to maintain the roll e' against the under side of the cam e^2 the rod e , and consequently the shipper-lever, will be forced upwardly in a gradual manner, thereby depressing the shipper-wheel E still deeper into the pulley F' , (and consequently withdrawing it from the pulley F a like distance,) thereby correspondingly reducing the speed of the driven pulley F and the spindles driven by it. At the same time the forward movement of the plate operates, through said connection n^3 and the tension device N , to gradually relax the pressure upon the yarn as the cop increases in diameter. When the cop has attained the desired or maximum size, the winding-head W is stopped and the now completed cop P removed from the spindle, thus completing the operation.

In Figs. 8 and 9 we have represented a modification of the variable pulley I shown in Figs. 1 and 2. In the latter the slight change required in the working diameter of the tapering pulley-rim is effected by forcing the rim into or out of the annular groove i^2 , the belt x traveling in a substantially invariable horizontal plane. In the modified arrangement the traveling belt passes between upper and lower arms r' , secured to the vertically-guided shipper-rod r , the latter having a spring r^2 at its lower end adapted to maintain it in engagement with the top adjusting-screw r^3 . The relative position of the belt on the pulley is effected by simply turning said screw in the proper direction, thereby correspondingly elevating or depressing the belt to the desired point on the tapered surface of the pulley's rim. An advantage resulting from this latter construction is that the vertical adjustment of the belt may be readily effected and without stopping the machine.

While the drawings represent the cam and cop spindles as being adapted to revolve in opposite directions, it is obvious that they may revolve in one direction, since either direction of rotation of the cam C will reciprocate the yarn-guide d equally well.

We claim as our invention and desire to secure by United States Letters Patent—

1. In a winding-machine of the class described, the combination of a revoluble spindle adapted to carry a cop tube or quill on which the cop is to be built, a reciprocating

- yarn-guide for laying the yarn in successive spiral convolutions and layers in building up the cop, a freely-turning guide-roll located contiguous to said yarn-guide and spindle,
- 5 a plate or frame member carrying said spindle capable of moving in a lateral direction in unison with and by means of the increasing diameter of the cop and having the peripheral surface of the latter in substantially continuous engagement with and having its movements controlled by said cam, a suitably-mounted revoluble cop-spindle capable of lateral movement in unison with and by means of the gradually-increasing diameter of the cop, and a freely-turning guide-roll d^2 located contiguous to the yarn-guide and in substantially continuous engagement with the cop's surface.
- 10 ous engagement with said guide-roll, a tension device for the yarn arranged whereby the tension is automatically relaxed as the cop increases in size, and driving mechanism for actuating said spindle having its speed automatically reduced by said increase in the cop's diameter.
- 15 2. In a winding-machine, the combination with a suitable driving-pulley, a cop-spindle and a variable pulley secured thereon, of an initial driven pulley, an endless driven belt leading from the latter pulley to said cop-spindle pulley, and a movable shipper wheel or member interposed between and adapted to be in simultaneous engagement with the driving and driven pulleys, substantially as hereinbefore described and for the purpose set forth.
- 20 3. In a winding-machine, the combination with the revoluble cop-spindle, a slideable plate or carriage having said spindle mounted therein, and a reciprocating guide for laying the yarn on the cop, of suitably-mounted yielding driving and driven pulleys through which power is transmitted to said spindle, a shipper-wheel interposed between and in frictional engagement with said pulleys, a movable arm or lever carrying said shipper-wheel, and means coacting with said carriage and lever arranged whereby the movement of the carriage, due to the increasing diameter of the cop, automatically changes the position of the shipper-wheel with respect to the said pulleys and produces a variation in the speed of the cop-spindle, substantially as described.
- 25 4. In a winding-machine, the combination of a vertically-arranged revoluble cam, a reciprocating yarn-guide actuated by said cam adapted to lay the yarn on the cop, a vertical cop-carrying spindle arranged to automatically move in a lateral direction away from the cam as the cop increases in size, an endless belt arranged to simultaneously actuate said cam and cop spindles, and mechanism substantially as described for automatically reducing the speed of the traveling belt as the cop increases in diameter.
- 30 5. In a winding-machine, the combination with the cop-spindle and a movable plate or frame carrying said spindle, of suitably-mounted driver and driven pulleys, a movable shipper device arranged to engage said pulleys having its action controlled by said plate, and a driving-belt mounted on said driven pulley and rotating the cop-spindle.
- 35 6. In a winding-machine, the combination of a revolving cam C having a fixed axis, a vertically-reciprocating yarn-guide d in engagement with the cop-spindle, a suitably-mounted cam and cop-spindle, and a reciprocating yarn-guide d^2 located contiguous to the cop-spindle and in substantially continuous engagement with the cop's surface.
7. In a winding-machine, the combination of oppositely-revolving pulleys F and g^2 , independently-mounted cam and cop carrying spindles, c^2 and H respectively, a pulley secured to said cop-spindle, an endless power-transmitting belt x in engagement with the said pulleys, intervening mechanism actuated by the said pulley g^2 for revolving the cam-spindle, and a reciprocating yarn-guide arranged with respect to the spindle H and having its movements controlled by the cam-spindle, substantially as described.
8. In a winding-machine, the combination with the revoluble vertically-arranged cam-carrying shaft or spindle c^2 and a pulley g^2 , through which power is transmitted for actuating said spindle, of the revoluble vertically-mounted and laterally-movable cop-carrying spindle H, a pulley secured thereto for actuating the spindle, an adjustably-mounted idler-pulley k adapted to revolve in a horizontal plane below said cop-spindle pulley, an initial driven pulley adapted to be actuated by any suitable driving means, and an endless open belt x in continuous engagement with said four pulleys, whereby when in use the cam and cop spindles are rotated at different rates of speed, substantially as described.
9. In a winding-machine, the combination with the suitably-mounted revoluble laterally-movable cop-spindle and the vertically-reciprocating yarn-guide d , of the yarn-tension device N provided with a pair of yielding friction-disks n' between which the yarn or thread passes, and a cam or wedge moving in unison with said cop-spindle, whereby as the cop increases in diameter the tension-cam gradually reduces the pressure upon the yarn between the friction-disks, substantially as described.
10. In a winding-machine, the combination of a cop-spindle and a slideable plate or carriage having said spindle revolubly mounted therein, means for driving said spindle, a reciprocating yarn-guide, a yielding tension device for the yarn having a member thereof connected with said movable carriage arranged to automatically reduce the tension upon the yarn as the cop increases in diameter, and means connected with the carriage and with said spindle-driving mechanism, whereby the speed of the spindle is automatically and gradually changed as the cop, which is being built thereon, increases in diameter, substantially as described.
11. In a winding-machine, the combination of a vertically-reciprocating yarn-guide, a

freely-turning guide-roll mounted contiguous to the delivery side of said yarn-guide, and a laterally-movable and revoluble cop-spindle having the surface of the cop, while being produced thereon, in substantially continuous engagement with the said guide-roll, substantially as described.

Signed at East Brookfield, Massachusetts, this 21st day of September, 1901.
